BILLFOLD

Harlan S. Cox, Danville, Ill.

Application June 11, 1951, Serial No. 230,946

4 Claims. (Cl. 150—38)

1

This invention relates to a new and improved billfold and more particularly to a holder for paper money especially designed for free access to the bills contained therein.

Usual types of billfolds contain pockets for holding bills, these pockets being open only along one side. With such containers it is difficult to distinguish the denomination of a bill without at least partially withdrawing the bill from the pocket. Also in many cases such billfolds are not adapted to receive and hold large numbers of bills. It is difficult to put many bills in the long pocket closed at one side and both ends. Also, when folded once across the middle as is customary, the container becomes bulky and distorted.

It is an object of the present invention to provide a new and improved billfold especially designed for the holding of paper money.

It is a further object to provide a construction which holds the bills adequately while permitting their ready inspection and removal as desired.

It is also an object to provide a construction which is simple in design and manufacture and which may be provided with additional pockets for holding cards or the like.

It is another object to provide a construction which may be formed from a blank cut from a single sheet of material and fabricated by means of a minimum of stitching or other securing means.

Other and further objects will appear as the description proceeds.

I have shown a preferred embodiment of my invention in the accompanying drawings in which—

Figure 1 is a plan view of a complete billfold in open position;

Figure 2 is a longitudinal section taken on line 2—2 of Figure 1, the fasteners being omitted;

Figure 3 is a cross section taken on line 3—3 of Figure 1;

Figure 4 is a plan view of a blank used for forming the billfold of Figures 1 to 3 inclusive; and

Figure 5 is a fragmentary plan view showing a modified form of holding lug.

In the drawings, referring first to Figure 4 the billfold may be formed from a single flat blank, as shown, having a body portion 11 integrally connected at one end along fold line 13 to an outer pocket portion 15 which is in turn connected along a side fold line 17 to an inner pocket portion 19. It will be noted that the outer edges 21 and 23 of the pocket portions 15 and 19 join in a rounded projection 25 in line with the fold line 13.

2

17. The body portion 11 is provided with a snap fastener member 27 adapted to mate with another fastener member 29 on the outer pocket portion 15 when the billfold is assembled and is folded to be placed in the pocket. It will be understood that other usual securing means may be substituted for the snap fastener if desired.

In assembling the billfold the inner pocket member 19 is first folded over on outer pocket member 15, being folded on line 17, with edge 31 of member 19 overlying edge 33 of member 15. It is to be noted that edge 35 of member 19 is offset below fold line 13 between body member 11 and outer pocket member 15. This allows space for the next folding operation which is made on line 13 and brings member 19 in contact with member 11. In this position the edges 31 and 33 overlie that portion of the edge 37 of the body member adjacent the fold line 13.

20. With the parts in position after this second folding operation, a single stitching operation will secure together edges 31 and 33 and the adjacent portion of edge 37. Instead of stitching, any well known method of securing edges of the material used may be carried out. It will be understood that the billfold may be formed of fabric, leather, plastic or from any suitable sheet material having sufficient body while also having sufficient flexibility and resistance to wear.

25. With the billfold assembled and with the edges secured, as described, a pocket for cards, indicated by broken lines at 39 in Figure 1, is provided between the inner pocket portion 19 and the outer pocket portion 15. The bottom of this pocket is closed by fold line 13. A money pocket for paper money is provided between the inner pocket portion 19 and the body portion 11. This pocket is proportioned so as to be substantially wider than the standard paper money and of a length somewhat more than one half the length of paper money. The money pocket is closed at its left end, as seen in Figure 2, by the fold on line 13 and on its lower edge by the stitching or other securing means.

30. The projection 25 on the fold line 17 when folded provides a stiff lug which extends beyond edge 21. This assists in holding the bills in place in the billfold. It will be noted that the width of the billfold is wider than standard paper money, indicated at 41 in broken lines on Figure 1, so that the lug 25 will be effective even when the billfold contains a substantial thickness of bills.

35. In Figure 5 an alternate construction has been shown for providing a separate holding lug instead of the folded projection 25 made of the material of the billfold. The adjacent folded

portion of the billfold has been indicated in Figure 5 at 43 and the holding lug is shown at 45. This lug, as shown, may be formed of metal, hard plastic or other suitable material and attached as a separate element to the folded inner and outer pocket portions at their edge, as shown in the drawing. It functions in the same manner as the holding lug 25 shown in Figure 1.

While I have shown and described a preferred embodiment of my invention this is to be understood to be illustrative only as it is capable of variation to meet differing conditions and requirements and I contemplate such modifications as come within the spirit and scope of the appended claims.

I claim:

1. A billfold formed of a unitary blank of flexible material, said billfold comprising a body member wider and longer than the bills to be carried, a pocket member integrally connected to one end of the body member, said pocket member being less than half the length of the body member and of substantially the same width as the body member and folded over on the body member, one free side edge of the pocket member being secured to the adjacent edge portion of the body member, and a bill holding lug extending from the free corner of the pocket member lengthwise of the body member.

2. A billfold formed of a unitary blank of flexible material, said billfold comprising a body member wider and longer than the bills to be carried, an outer pocket portion less than one half the length of the body member and substantially the width of the body member integrally connected to one end of the body member, an inner pocket portion integrally connected to a side edge of the outer pocket portion, the inner pocket portion being folded over onto the inner face of the outer pocket portion, the combined pocket portions being folded over on the inner face of the body member, and the free side edges of the pocket members being secured to the adjacent edge portion of the body member.

3. A billfold formed of a unitary blank of flex-

45

ible material, said billfold comprising a body member wider and longer than the bills to be carried, an outer pocket portion less than one half the length of the body member and substantially the width of the body member integrally connected to one end of the body member, an inner pocket portion integrally connected to a side edge of the outer pocket portion, the inner pocket portion being folded over onto the inner face of the outer pocket portion, the combined pocket portions being folded over on the inner face of the body member, and the free side edges of the pocket members being secured to the adjacent edge portion of the body member, a bill holding lug extending lengthwise of the body member from the inner end of the folded edges of the inner and outer pocket member, and cooperating securing means on the body member and outer pocket member to hold the parts detachably in folded position.

4. In a billfold, a body member wider and longer than the bills to be carried and a pocket member attached to one end of the body member, the pocket member being substantially the same width and less than one half the length of the body member, the pocket member being folded over against the body member and secured to a portion of one side of the body member, the free corner of the pocket member being provided with a bill holding lug projecting longitudinally of the body member.

HARLAN S. COX.
